UNITED STATES PATENT OFFICE.

CARL AUGUST RUDQVIST, OF STAKET, SWEDEN, ASSIGNOR TO J. & C. G. BOLINDERS MEKANISKA VERKSTADS AKTIEBOLAG, OF STOCKHOLM, SWEDEN, A COMPANY OF SWEDEN.

SPARK-PLUG VALVE FOR PETROLEUM AND CRUDE-OIL ENGINES.

Application filed September 22, 1921. Serial No. 502,538.

To all whom it may concern:

Be it known that I, CARL AUGUST RUDQVIST, a subject of the King of Sweden, residing at Staket, in the Kingdom of Sweden, have invented a new and useful Improvement in Spark-Plug Valves for Petroleum and Crude-Oil Engines, of which the following is a specification.

The present invention relates to a spark plug valve for petroleum and crude oil engines, in which the spark plug is fitted in a movable valve body which is provided with two oppositely arranged valve faces which cooperate with two corresponding valve seat faces on a stationary sleeve in which the valve body is guided, in such manner that the valve body obtains two definite closing positions, in the one of which the spark plug is in open communication with the combustion chamber of the engine, and in the other of which it is shut off from said chamber.

The invention is characterized by this that the means for guiding the valve body in the stationary sleeve is located entirely outside both of said valve seat faces, so that in both closing positions of the valve body the guide surfaces are shut off from the combustion chamber. In this manner it is avoided that the products of combustion arrive between the guide surfaces and thereby obstruct or render difficult the movements of the valve body.

The accompanying drawings illustrate by way of example an embodiment of the invention. Fig. 1 shows a section through the ignition chamber of an engine provided with a spark plug valve according to the invention fitted in the wall of the ignition chamber, said valve being adjusted in one closing position, and Fig. 2 shows a similar section, the valve being adjusted in the other closing position. Fig. 3 shows a section through the valve body on the line III—III in Fig. 1, Fig. 4 shows a top plan view of the ignition chamber and the spark plug valve, and Fig. 5 shows a detail of the adjustment device resembling a bayonet joint.

Referring to the drawings, 1 denotes the ignition chamber of the engine, or the so-called ignition cap, in the upper portion of which an injection nozzle 2 is fitted in the ordinary manner, by means of which nozzle the fuel—petroleum or crude oil—is injected and sprayed in the ignition chamber as in-

dicated in Fig. 1. In the side wall of the ignition chamber 1 the spark plug valve is fitted. Said valve comprises the valve body 3, 4 and a member 5 surrounding the valve body and having the shape of a substantially cylindrical sleeve, said member being secured to the ignition chamber over an opening in the side wall of said chamber. The member 5 as well as the portion of the wall of the ignition chamber surrounding the nozzle 2 are provided with water jackets. The valve body comprises two parts, the inner part 3 of which is screwed into the outer part 4 and retained in the same by means of a stop screw 6. The outer part 4 consists of a substantially cylindrical sleeve which is fitted in the sleeve 5 and is slideable and rotatable in the same, whereas the inner part 3 consists of a cylindrical sleeve and a head 3^a rigidly connected with the sleeve by means of two diametrically opposed extensions 3^a of the wall of the sleeve. The sleeve 3 is threaded internally for receiving the spark plug 7. In the embodiment illustrated said spark plug is provided with a spark gap 8 and with a current carrying heating plate 9 which serves to vaporize a portion of the injected fuel which is afterwards ignited by the sparks in the spark gap.

According to the invention the valve body 3, 4 is provided with two oppositely arranged conical valve faces 10 and 11 which cooperate with two corresponding valve seat faces 12 and 13 on a flange 14 projecting inwards from the stationary sleeve 5, so that the valve body becomes a double valve with two definite closing positions. One of said positions is shown in Fig. 1 in which the faces 10 and 12 bear against one another, and the spark plug is in operative position, that is to say in open communication with the interior of the ignition chamber, and the other position is shown in Fig. 2 in which the faces 11 and 13 bear against one another, so that the spark plug is shut off from the interior of the ignition chamber. In this manner a reliable tightness is obtained in both of said positions. It will be evident from Figs. 1 and 2 that the surfaces which guide this longitudinal movement of the valve body 3, 4, in the stationary sleeve 5, i. e., the outer cylindrical surface of the body 4 and the inner cylindrical surface of the sleeve 5 are located entirely outside the

two valve seat faces 12 and 13, so that in both closing positions of the valve body 3, 4 said cylindrical guide surfaces are shut off from the ignition chamber and are thus protected from products of combustion penetrating in between said guiding surfaces. The adjustment of the valve body from one position to the other is effected by means of two handles 15 secured to the sleeve 4 and 10 engaging slots 16 in the stationary sleeve 5. One of said slots 16 is shown developed in Fig. 5. As shown in this figure the handles and the slots form together a bayonet joint, so that by sliding and turning the valve body in the sleeve 5 said body may be adjusted and secured in any of the two closing positions illustrated in Figs. 1 and 2. When the handles 15 occupy the position in the slots indicated by means of the dotted 20 and dashed circle 15^a in Fig. 5 the valve body 3, 4 is secured in the position shown in Fig. 1, and when the handles occupy the position indicated by means of the circle 15^b in Fig. 5 the valve body is secured in the 25 position shown in Fig. 2. As shown in Fig. 5 the edges of the slots 16 against which the handles 15 bear in both of said positions, incline slightly relatively to a plane perpendicular to the longitudinal axis of the sleeve 30 5, so that by turning the valve body an efficient contact between the valve faces 10 and 12, or 11 and 13, may always be obtained.

In the position of the valve body 4, 3, 3^a, 35 3^b shown in Fig. 1 the spark gap and the heated plate of the spark plug are in open communication through the apertures between the two extensions 3^a with the interior of the ignition chamber 1, the valve body being so positioned that a portion of the injected fuel impinges on the heated plate 9, and when said plate is sufficiently hot, said fuel will be vaporized adjacent the spark gap 8 and will immediately become ignited 40 by the sparks in said gap. When the engine has been started in this manner, and the walls of the ignition chamber have become heated to such extent that the ignition becomes spontaneous, the valve body is moved 45 by means of the handles 15 to the position shown in Fig. 2 so that the spark plug is shut off from the ignition chamber. The spark plug may then be removed for inspection, for instance by means of a key introduced into the sleeve 4, without interfering 50 with the operation of the engine.

I claim:

1. In a spark plug valve for petroleum and crude oil engines, the combination of a 60 sleeve having two oppositely arranged valve seat faces, a valve body movable in said sleeve and provided with two oppositely arranged valve faces adapted to cooperate with said valve seat faces on said sleeve, said valve body having an aperture between said

valve faces, a spark plug inserted in said valve body and having a spark gap located opposite said aperture in said valve body, and means for guiding said valve body in said sleeve into two positions in each of 70 which one valve face on said valve body bears against one valve seat face on said sleeve, and in one of which positions said aperture in said valve body for said spark gap projects outside said sleeve and in the 75 other position said aperture is retracted within said sleeve, said guiding means being located entirely to one side of both of said valve seat faces removed from said aperture. 80

2. In a spark plug valve for petroleum and crude oil engines, the combination of a sleeve having two oppositely arranged valve seat faces at one end and at least one substantially helical slot at its other end, a valve body movable in said sleeve and provided at one end with two oppositely arranged valve faces adapted to cooperate with said valve seat faces on said sleeve, said valve body having an aperture between said valve faces, at least one handle secured to the other end of said valve body and adapted to slide in said slot in said sleeve and thereby to secure said valve body in said sleeve in two positions in each of which one valve face on said valve body bears against one valve seat face on said sleeve, and in one of which positions said aperture in said valve body projects outside said sleeve and in the other position said aperture is retracted within said sleeve, and a spark plug inserted in said valve body and having a spark gap located opposite said aperture in said valve body. 90

3. In an ignition plug valve for petroleum and crude oil engines, the combination of a sleeve having two oppositely arranged valve seat faces, a valve body movable in said sleeve and provided with two oppositely arranged valve faces adapted to cooperate with said valve seat faces on said sleeve, said valve body having an aperture between said valve faces, means for guiding said valve body in said sleeve and means for securing said valve body in two positions in each of which one valve face on said valve body bears against one valve seat face on said sleeve, and in one of which positions said aperture in said valve body projects outside said sleeve and in the other position said aperture is retracted within said sleeve, said guiding means being located entirely to one side of both of said valve seat faces removed from said aperture. 105

4. In an ignition plug valve for petroleum and crude oil engines, the combination of a sleeve having two oppositely arranged valve seat faces at one end and at least one substantially helical slot at its other end, a 110

115

120

125

- valve body movable in said sleeve and provided at one end with two oppositely arranged valve faces adapted to cooperate with said valve seat faces on said sleeve, 5 said valve body having an aperture between said valve faces, and at least one handle secured to the other end of said valve body and adapted to slide in said slot in said sleeve and thereby to secure said valve body 10 in said sleeve in two positions in each of which one valve face on said valve body bears against one valve seat face on said sleeve, and in one of which positions said aperture in said valve body projects outside said sleeve and in the other position said aperture is retracted within said sleeve.
5. In a spark plug valve for petroleum and crude oil engines, the combination of a sleeve having two oppositely arranged valve 20 seat faces, a valve body movable in said sleeve and provided with two oppositely arranged valve faces adapted to cooperate with said valve seat faces on said sleeve, said valve body having an aperture between said valve faces, a spark plug inserted in said valve body and having a spark gap and an electric heating element located opposite said aperture in said valve body, means for guiding said valve body in said sleeve and 25 means for securing said valve body in two positions in each of which one valve face on said valve body bears against one valve seat face on said sleeve, and in one of which positions said aperture in said valve body for said spark gap projects outside said sleeve and in the other position said aperture is retracted within said sleeve, said guiding means being located entirely to one side of both of said valve seat faces removed from 30 said aperture.
6. In a spark plug valve for petroleum and crude oil engines, the combination of a sleeve having two oppositely arranged valve seat faces at one end and at least one substantially helical slot at its other end, a valve body movable in said sleeve and provided at one end with two oppositely arranged valve faces adapted to cooperate with said valve seat faces on said sleeve, 40 said valve body having an aperture between said valve faces, at least one handle secured to the other end of said valve body and adapted to slide in said slot in said sleeve and thereby to secure said valve body in said sleeve in two positions in each of which one valve face on said valve body bears against one valve seat face on said sleeve, and in one of which positions said aperture in said valve body projects outside said sleeve and in the other position said aperture is retracted within said sleeve, and ignition means in said valve body opposite said aperture in said valve body.
7. In an ignition plug valve for petroleum and crude oil engines, the combination of a sleeve having two oppositely arranged valve seat faces, a valve body movable in said sleeve and provided with two oppositely arranged valve faces adapted to cooperate with said valve seat faces on said sleeve, said valve body having an aperture between said valve faces, ignition means in said valve body opposite said aperture in said valve body, means for guiding said valve body in said sleeve and means for securing said valve body in two positions in each of which one valve face on said valve body bears against one valve seat face on said sleeve, and in one of which positions said aperture in said valve body projects outside said sleeve and in the other position said aperture is retracted within said sleeve, said guiding means being located entirely to one side of both of said valve seat faces removed from said aperture.
8. In an ignition plug valve for petroleum and crude oil engines, the combination of a sleeve having two oppositely arranged valve seat faces at one end and at least one substantially helical slot at its other end, a valve body movable in said sleeve and provided at one end with two oppositely arranged valve faces adapted to cooperate with said valve seat faces on said sleeve, said valve body having an aperture between said valve faces, at least one handle secured to the other end of said valve body and adapted to slide in said slot in said sleeve and thereby to secure said valve body in said sleeve in two positions in each of which one valve face on said valve body bears against one valve seat face on said sleeve, and in one of which positions said aperture in said valve body projects outside said sleeve and in the other position said aperture is retracted within said sleeve, and ignition means in said valve body opposite said aperture in said valve body.
9. In an ignition plug valve for petroleum and crude oil engines, the combination of a sleeve having two oppositely arranged valve seat faces, a valve body movable in said sleeve and provided with two oppositely arranged valve faces adapted to cooperate with said valve seat faces on said sleeve, said valve body having an aperture between said valve faces, and means for guiding said valve body in its movement to either of two positions in each of which one valve face on said valve body bears against one valve seat face on said sleeve and in one of which positions said aperture in said valve body projects outside of said sleeve and in the other position said aperture is retracted within said sleeve.

within said sleeve, said means being located entirely to one side of both of said valve seat faces removed from said aperture.

10. In a device of the class described, the combination with an engine cylinder, and a sleeve having a pair of valve seat faces, a valve body in said sleeve, said valve body having a pair of valve faces, a spark plug carried by said valve body, said spark plug

being in communication with the gas in 10 said cylinder when one of said valve faces coacts with one of said valve seat faces, said spark plug being closed to said gas when said other valve face coacts with said other valve seat face, and means for guiding 16 said valve body to cause either of said valve faces to co-operate with its respective seat.

CARL AUGUST RUDQVIST.
